UNITED STATES PATENT OFFICE

HOWARD M. LEONARD, OF SOUTH BEND, INDIANA, ASSIGNOR TO GERNANDT MOTOR CORPORATION, OF CHICAGO, ILLINOIS, A CORPORATION OF ILLINOIS

ENGINE

Application filed June 2, 1927. Serial No. 195,959.

This invention relates to engines, and is illustrated as embodied in an internal combustion engine of the injection type. An object of the invention is to provide improved means for injecting the fuel, and for providing for practically complete vaporization of each charge of fuel in a fluid medium such as air or exhaust gas.

Preferably means for compressing the fluid medium, with the fuel, is provided at the side of the engine cylinder, for example by a compression plunger in a compression cylinder communicating with a relatively large compression chamber in the center of the cylinder head. This compression chamber may be large enough to receive several mixed and compressed charges of the fluid, and I prefer to control the injection of the charges into the engine cylinder by a relatively large valve, illustrated as being of the mushroom type, and which directs the fuel charge in a relatively flat cone into all parts of the engine cylinder.

The above and other objects and features of the invention, including various novel and desirable features of construction, will be apparent from the following description of one illustrative embodiment shown in the accompanying drawings, in which:

Figure 1 is a vertical section through the upper part of the engine cylinder and through the fuel-feeding means; and

Figure 2 is a side elevation, partly broken away in vertical section, of the lower part of the fuel-feeding plunger.

The illustrated engine includes a water-cooled cylinder 10, with the usual water-cooled cylinder head 12 detachably arranged at its upper end, and containing the engine piston 14. Piston 14 has a central projection 16 at its upper end, thus defining, when at the upper end of its stroke, an annular combustion space 18.

Approximately at the center of the cylinder head 12, there is formed a compression chamber 20, having a communicating passage 22 extending toward the side of the cylinder head, and having the shape of an inverted cup of relatively large size and closed by a valve 24, preferably of mushroom form, which

serves when open to direct the charge of vaporized fuel in a relatively flat cone into the combustion space 18, where it is ignited by the extremely hot compressed air in the engine cylinder.

At one side of the engine, a compression cylinder, communicating with passage 22 at its upper end, is formed partly in the wall of the engine cylinder 10 and partly in the cylinder head 12. In this compression cylinder is arranged a novel plunger including two sections 26 and 28 (which may be urged apart if desired by short coil springs arranged between the sections in registering sockets formed in their adjacent faces). At their lower ends, the sections are formed with registering semispherical sockets receiving the semispherical head 30 of a cam-actuated operating plunger section 32, shown with piston rings 34. Above the flat upper surface of the head 30, is arranged a packing 36 of hard Babbitt metal or the like, which is compressed by the head 30 on each upward stroke, to seal the joint between the two sections 26 and 28 and to urge the sections apart against the wall of the compression cylinder. On the downward stroke of the compression plunger, a charge of fuel and a charge of air or exhaust gas or other fluid medium, is introduced into the compression cylinder, for example through a passage 38 controlled by a valve 40. This charge is forced under considerable pressure into the chamber 20 on the upward stroke of the compression plunger.

While one illustrative embodiment has been described in detail, it is not my intention to limit the scope of the invention to that particular embodiment, or otherwise than by the terms of the appended claims.

I claim:

1. Fuel-feeding means for an engine comprising, in combination, a cylinder head having a relatively large fuel mixture compression chamber in the form of an inverted cup at its center, a relatively large mushroom valve controlling the opening at the mouth of said cup, and fluid-compression means communicating with said chamber, said valve having diverging edges adapted to direct the mixture toward the cylinder head walls.

2. An engine of the fuel injection type comprising, in combination, a cylinder and piston, said cylinder having a dome-shaped head provided with an axially positioned inverted cup-shaped compression chamber cavity separated therefrom by an outwardly flaring valve mounted in the head and convex on the side toward the cylinder, and said piston provided with an axially convex protuberance defining an annular space within the head communicating with the compression chamber cavity when the valve is open.
